CLAIM

The ornamental design for a connector housing for medical optical fibers, as shown and described.

DESCRIPTION

1.1 is a perspective view of a connector housing for medical optical fibers showing our new design;

1.2 is a front elevational view thereof;

1.3 is a rear elevational view thereof;

1.4 is a right side elevational view thereof;

1.5 is a left side elevational view thereof;

1.6 is a top plan view thereof; and

1.7 is a bottom plan view thereof.

In the drawings, the evenly-spaced broken lines depict portions of the connector housing for medical optical fibers that form no part of the claimed design. Additionally, the dash-dot-dash broken lines define the boundaries of the claimed design.

1 Claim, 4 Drawing Sheets
